United States Patent Office

Des. 184,388
Patented Feb. 10, 1959

184,388

BUS

Robert E. Bourke, Westport, Conn., assignor to Mack
Trucks, Inc., Plainfield, N. J., a corporation of New York

Application June 25, 1958, Serial No. 51,514

Term of patent 14 years

(Cl. D14—3)

FIG.1.

Des. 184,388

PAGE 2

FIG. 2.

Des. 184,388

FIG. 3.

FIG. 4.

The dominant features of my design reside in the portions shown in full lines.

I claim:

The ornamental design for a bus, as shown and described.
